UNITED STATES PATENT OFFICE.

ALFRED G. F. KUROWSKI, OF BROOKLYN, NEW YORK, ASSIGNOR TO UNDERWOOD
TYPEWRITER COMPANY, OF NEW YORK, N. Y., A CORPORATION OF DELAWARE.

TYPEWRITING MACHINE.

Application filed September 30, 1920. Serial No. 413,671.

To all whom it may concern:

Be it known that I, ALFRED G. F. KUROWSKI, a citizen of the United States, residing in Brooklyn Borough, in the county of 5 Kings, city and State of New York, have invented certain new and useful Improvements in Typewriting Machines, of which the following is a specification.

This invention relates to feed-roll releasing mechanism for typewriting machines, 10 and is in the nature of an improvement on the invention pointed out in my co-pending application, Serial No. 305,114, filed June 18, 1919, and now Patent No. 1,367,784, 15 dated February 8, 1921.

In said patented invention, the front and rear feed-rolls are supported by means of hangers, common thereto, which are fixed on a supporting shaft at points intermediate 20 their ends. The shaft, just referred to, is mounted in slotted brackets so as to be guided thereby to permit movement to and from the platen, and the feed-rolls are normally held in engagement with the platen 25 by means of springs acting on the hangers near their rear ends, these springs being supported at their lower ends by holders adjustably positioned on a flanged tie-member connecting the ends of the platen-frame, 30 means being provided effective to cast off both feed-rolls against the tension of the springs.

In the embodiment of the invention herein disclosed, the shaft, to which the hangers 35 are fixed, is provided with flattened portions which are embraced by slotted brackets, and arrangement which permits movement of the shaft toward and from the platen, but prevents rotation thereof. In 40 order to withdraw said shaft from the platen, provision is made of arms rigidly extending rearwardly and downwardly from the hubs by which the hangers are fixed on the shaft, and said arms are provided with closed vertical slots through 45 which passes a feed-roll-release or cast-off shaft, so shaped that, upon rotation, it will exert a camming action on the bottom walls of the slot. It will be seen that by placing 50 the feed-roll-release shaft intermediate the springs and the shaft on which the hangers are fixed, there will be a decreased turning tendency of the hangers about the hanger-carrying shaft due to the action of the 55 springs, relatively to what this tendency

would be with the release shaft otherwise placed. Preferably, the cross-sections of the cam-portions of the feed-roll-release shaft are in the form of segments of circles, and the feed-roll-release or cast-off lever is so connected therewith that, when actuated, the shaft will be turned so as to maintain the rounded portion thereof in contact with the rear walls of the slots of the rearwardly and downwardly extending arms, thereby tending to prevent rotation of the hangers about the hanger-carrying shaft due to the springs. The turning tendency, due to said springs, is also guarded against by providing the rearwardly and downwardly extending arms 60 with portions having vertical faces engaging a vertical flange at the rear of the flanged tie-member. It will be seen that, as a result of the present structure, the feed-rolls may be moved to and from the platen in substantially straight lines, and that there will be no marked tendency to cramp the flattened portions of the hanger-carrying shaft in the slotted guiding plates. 65

Other features and advantages will hereinafter appear.

In the accompanying drawings,

Figure 1 is a fragmentary perspective view, partly in section, of a platen-frame with my invention applied thereto, and with the feed-rolls in co-operative relation with the platen. 75

Figure 2 is a fragmentary side view, obtained by looking at the structure of Figure 1 from the left, and showing the position of the parts when the feed-rolls are in position to co-operate with the platen, similarly to Figure 1. 80

Figure 3 is a view similar to Figure 2, but showing the position of the parts when the feed-rolls are cast off. 85

Referring to the drawings, the platen 1 is mounted in the end members 2 of the platen-frame, and the front and rear feed-rolls 3 and 4, which co-operate therewith, are carried by shafts 5 and 6, respectively. The feed-roll shafts 5 and 6 are supported at the opposite ends of hangers 7, the hubs 8 of which are fixed on a shaft 9 whose flattened ends 10 are guided for vertical movement in slotted plates 11, supported in a flanged tie-member 12, connecting the end members 2 of the platen-frame. 90

In order to yieldingly press the feed-rolls 105 against the platen, provision is made of 110

springs 13, connected at their upper ends with spring-clips 14 embracing the rear arms of the hangers 7 and permitting movement therealong to determine the points 5 at which the springs will act on said hangers. At their lower ends, springs 13 are connected with holders 15, which may be adjusted in position in the flanged tie-member 12 by means of adjusting screws 16 10 and 17.

The hubs 8 of hangers 7 are provided with arms 18 extending rearwardly and downwardly therefrom at the rear of and to a lower level than the hanger-carrying 15 shaft 9, said arms 18 being provided with portions 19, the rear faces of which engage with an upright flange 20 of the tie-member 12, to be guided thereby, for vertical movement. The arms 18 project rigidly from the 20 hangers 7 and, in the particular construction shown in the drawings, are formed in one piece therewith. The arms 18 are provided with closed vertical slots 21 through 25 which passes feed-roll-release shaft 22, journaled in the end members 2 of the platen-frame. The portions of said shaft 22 passing through the slots 21 are preferably segmental in cross-section and said shaft is normally in the position shown in Figures 1 and 2.

When it is desired to release or cast off the feed-rolls the feed-roll-release lever 23, pivoted at 24 on right-hand end member 2 of the platen-frame, may be depressed, 35 and, through link 25 and arm 26, mounted on the shaft 22, the latter may be turned in a counterclockwise direction from the position shown in Figure 2 to that shown in Figure 3.

40 The cam portion of the feed-roll-release shaft 22 acts against the bottom wall of the slot 21 in the arm 18 to force downward this arm together with the hanger-carrying shaft 9 and hanger 7 to cast off the feed-rolls 3 and 4. When the feed-rolls are cast off, the rounded portion of the cast-off shaft or cam-shaft 22 is maintained in engagement with the rear wall of the slot 21. The hanger 7 is guided for straight vertical movement, and its tendency to rock, due to the action of the spring 13 and cam-shaft 22, is prevented by means of the co-operating guiding action of the ends 10 of the hanger-shaft 9, guided in the slotted plates 45 11, and the arm 18, guided between the flange 20 of the tie-member 12 and the rounded portion of the cast-off shaft 22. It is to be noted that the cam-shaft 22 is effective, through the arm 18, to apply roll-withdrawing force to the hanger 7 nearer to the end thereof where the spring 13 is effective thereon than to the other end thereof, and along a vertical line at the same side of the shaft 9 as the point of application 50 of the spring 13, thereby to counter-

act and diminish the tendency of the hanger 7 to rock under the opposed forces of the spring 13 and the roll-releasing cam of the cam-shaft 22.

Provision may also be made of a shield 70 27 similar to that disclosed in the Patent, No. 1,315,559, granted to me September 9, 1919, said shield being provided with slotted brackets 28 embracing the shaft 22.

Variations may be resorted to within the 75 scope of the invention, and portions of the improvements may be used without others.

Having thus described my invention, I claim:

1. In a typewriting machine, in combination, a platen, front and rear feed-rolls, hangers common to both front and rear feed-rolls, a shaft on which said hangers are carried, guides for said shaft, springs acting on said hangers at one side of said shaft, and means for withdrawing said hangers and, consequently, said rolls from the platen, acting to apply force to said hangers along lines at the same side of said shaft as the points of application of said springs, so as to counteract the twisting tendency about said shaft of the hangers due to said springs and means. 85

2. In a typewriting machine, in combination, a platen, front and rear feed-rolls, hangers common to both front and rear feed-rolls, a shaft on which said hangers are mounted, said shaft having flattened 95 portions, slotted guides to receive the flattened portions of said shaft to prevent rotation of the same, springs acting on said hangers at one side of said shaft, and means for withdrawing said rolls from the platen, acting to apply force to said hangers along 100 lines at the same side of said shaft as the points of application of said springs, so as to counteract the twisting tendency about said shaft of the hanger due to said springs and means. 105

3. In a typewriting machine, in combination, a platen, front and rear feed-rolls, supporting means for said feed-rolls including hangers, common to both front and rear feed-rolls, means acting on each of said hangers near one of its ends, urging the hangers towards the platen, and means for withdrawing said hangers, effective to apply force to said hangers nearer to the ends thereof where said urging means are effective thereon than to the other ends thereof. 110

4. In a typewriting machine, in combination, a platen, front and rear feed-rolls, supporting means for said feed-rolls including hangers common to both front and rear feed-rolls, members projecting rigidly from each of said hangers, a guide for each of said members to permit movement of the corresponding hangers toward and from the platen, means acting on each of said hangers near one of its ends to urge the same towards 120 125 130

the platen, and means for withdrawing said hangers from the platen, effective to apply force to said hangers nearer to the ends thereof where said urging means are effective 5 thereon than to the other ends thereof, thereby to reduce the tendency of said hangers to turn about the guide for said members.

5. In a typewriting machine, the combination with a platen and front and rear feed-
10 rolls mounted on front and rear shafts, respectively, of hangers for supporting said shafts, a shaft on which said hangers are fixed, guiding means for the hanger-carrying shaft permitting movement thereof to and
15 from the platen, resilient means acting on said hangers at one side of the hanger-carrying shaft, to urge the feed-rolls towards the platen, arms fixed on the hanger-carrying shaft, and extending toward said resilient
20 means, and feed-roll-withdrawing means acting on said arms near said resilient means to diminish the turning effect resulting from the upward thrust of the resilient means and the downward pull of the feed-roll-with-
25 drawing means.

6. In a typewriting machine, in combination, a platen, front and rear feed-rolls, a shaft for said front feed-roll, a shaft for said rear feed-roll, hangers common to both
30 of said shafts, a shaft on which said hangers are fixed, said hanger-carrying shaft being mounted for movement to and from the platen, but held against rotation, a spring device acting on each of said hangers near
35 the rear feed-roll shaft, to urge said feed-rolls toward the platen, said spring devices being adapted to be adjusted to and from said feed-rolls, arms extending downwardly and rearwardly from said hanger-carrying
40 shaft, guiding means for said arms, acting to prevent turning of said shaft under the action of said spring devices, and a device acting on said arms in a plane passing between the hanger-carrying shaft and said
45 spring devices to withdraw said hanger-carrying shaft, and, consequently, said feed-rolls from said platen.

7. In a typewriting machine, in combination, a platen, front and rear feed-rolls, hangers common to both front and rear feed-
50 rolls, a shaft on which said hangers are fixed, guides for said shaft, said shaft and said guides having co-operating parts whereby turning of said shaft in said guides is
55 prevented, springs acting on said hangers at one side of said shaft, and means for withdrawing said hangers and consequently said rolls from the platen, acting to apply force to said hangers at the same side of said shaft
60 as the points of application of said springs.

8. In a typewriting machine, in combination, a platen, front and rear feed-rolls normally engaging the lower part of the platen, hangers common to both front and rear feed-
65 rolls, a shaft on which said hangers are fixed,

guides for said shaft, springs acting on said hangers at one side of said shaft to urge said feed-rolls toward the platen, arms fixed on said shaft and extending in a direction to bring the free ends thereof adjacent the vertical plane in which lie the points of application of said springs, and a cam-device to act on said arms near their free ends. 70

9. In a typewriting machine, in combination, a platen, front and rear feed-rolls normally engaging the lower part of the platen, hangers common to both front and rear feed-rolls, a shaft on which said hangers are fixed, guides for said shaft, said shaft and said guides having co-operating parts whereby turning of said shaft in said guides will be prevented, springs acting on said hangers at one side of said shaft to urge said feed-rolls toward the platen, arms fixed on said shaft and extending in a direction to bring the free ends thereof adjacent the vertical plane in which lie the points of application of said springs, and a cam-device to act on said arms near their free ends. 75 80 85

10. In a typewriting machine, in combination, a platen, front and rear feed-rolls normally engaging the lower part of the platen, hangers common to both front and rear feed-rolls, a shaft on which said hangers are fixed, guides for said shaft, springs acting on said hangers at one side of said shaft to urge said feed-rolls toward the platen, arms fixed on said shaft and extending in a direction to bring the free ends thereof adjacent the vertical plane in which lie the points of application of said springs, a cam-device to act on said arms near their free ends, and guiding means engaging the free ends of said arms, so as to resist the tendency to turn said shaft, due to the thrust of the springs and action of the cam-device, without interfering with the casting off of said feed-rolls. 90 95 100 105

11. In a typewriting machine, in combination, a platen, front and rear feed-rolls normally engaging the lower part of the platen, hangers common to both front and rear feed-rolls, a shaft on which said hangers are fixed, guides for said shaft, springs acting on said hangers at one side of said shaft, arms fixed on said shaft, said arms having vertical slots, a release-shaft passing through said slots, said release-shaft being cut away on one side to form flat surfaces which normally engage the bottom walls of said slots, and means to actuate said release-shaft in a direction which will maintain the rounded surface thereof in contact with the proper side walls of the slots to resist rotation about the hanger-carrying shaft. 110 115 120

12. In a typewriting machine, in combination, a platen, front and rear feed-rolls normally in engagement therewith, hangers common to both front and rear feed-rolls, a shaft on which said hangers are fixed, means to limit the movement of said shaft to a pre- 125 130

determined path and to prevent turning thereof, resilient devices acting on said hangers at one side of said shaft to urge the feed-rolls against the platen, and means for releasing said feed-rolls including arms extending from said hangers adjacent the shaft towards said resilient devices, and a cam-device to engage said arms at points adjacent said resilient devices.

13. In a typewriting machine, in combination, a platen, front and rear feed-rolls normally in engagement therewith, means to support said feed-rolls including a shaft, hangers common to both front and rear feed-rolls, having hubs fixed on said shaft, arms extending downwardly and rearwardly from said hubs, resilient devices acting on said hangers at the side of said shaft from which said arms extend, and means acting on said arms at points near said resilient devices to release said feed-rolls.

14. In a typewriting machine, in combination, a platen, front and rear feed-rolls normally engaging the lower part of the platen, hangers common to both front and rear feed-rolls, a shaft on which said hangers are fixed, guides for said shaft, resilient devices acting on said hangers at one side of said shaft to urge said feed-rolls toward the platen, arms fixed on said hangers adjacent said shaft and extending toward said resilient devices, and a releasing device acting on said arms at points adjacent a vertical plane through the points of application of said resilient devices.

15. In a typewriting machine, in combination, a platen, front and rear feed-rolls normally in position to co-operate with the lower part of the platen, hangers common to both front and rear feed-rolls, a shaft on which said hangers are fixed, guides for said shaft, springs acting on said hangers at one side of said shaft to urge said feed-rolls toward the platen, arms fixed on said shaft and extending in a direction to bring the free ends thereof adjacent the vertical plane in which lie the points of application of said springs, a cam-device to act on said arms near their free ends to cast off the feed-rolls, and means for guiding the free ends of said arms to co-operate with the guides for the shaft to prevent rocking movement of the hangers.

16. In a typewriting machine, in combination, a platen, front and rear feed-rolls normally co-operating with the lower part of the platen, a hanger common to both front and rear feed-rolls, a hanger-carrying shaft on which said hanger is mounted, substantially vertical guides for said shaft, springs acting on said hanger at one side of said shaft tending to press said feed-rolls into co-operative relation with the platen, an arm having a rigid connection to the hanger and projecting to a level different from said

shaft, said arm having a substantially vertical closed slot therein, a feed-roll-release shaft passing through said slot at a level different from that occupied by said hanger-carrying shaft, said release shaft having a rounded portion forming a surface in engagement with one of the side walls of the slot and having a depressed cam portion forming a cam surface which normally engages the bottom wall of the slot, means to rock said release shaft to cast off the feed-rolls while maintaining the rounded portion or surface thereof in engagement with the side wall of the slot to prevent rocking movement of the hanger about the hanger-carrying shaft in one direction, and a guide for said arm to prevent rocking movement of the hanger in the opposite direction.

17. In a typewriting machine, in combination, a platen, front and rear feed-rolls normally in position to co-operate with the lower part of the platen, a hanger common to both front and rear feed-rolls, a hanger-carrying shaft on which said hanger is mounted, a substantially vertical guide for said shaft, a spring acting on said hanger at one side of said shaft to urge said feed-rolls toward the platen, an arm rigid with the hanger and extending to a lower level than said shaft at the same side thereof as the spring, a releasing device acting on said arm to move the hanger against the tension of said spring for casting off the feed-rolls, and means for substantially vertically guiding the free end of said arm to co-operate with the guide for said shaft to prevent rocking movement of the hanger.

18. In a typewriting machine, in combination, a platen, front and rear feed-rolls normally occupying a position to co-operate with the lower part of the platen, a hanger common to both front and rear feed-rolls, a spring effective on the hanger nearer to one of the feed-rolls than to the other to urge both feed-rolls toward the platen, means for guiding the hanger for up-and-down movement and for restraining it against rocking movement, and a cast-off device effective to apply roll-withdrawing force to the hanger at a point nearer to the feed-roll where the spring is effective than to the other feed-roll.

19. In a typewriting machine, in combination, a platen, front and rear feed-rolls normally occupying a position to co-operate with the lower part of the platen, a hanger common to both front and rear feed-rolls, a spring effective on the hanger between the feed-rolls and at a point nearer to one of the feed-rolls than to the other, and a cast-off device effective to apply roll-withdrawing force to the hanger between the feed-rolls and at a point nearer to the feed-roll where the spring is effective than to the other feed-roll.

20. In a typewriting machine, in combination, a platen, front and rear feed-rolls normally occupying a position to co-operate with the lower part of the platen, a hanger 5 common to both front and rear feed-rolls, a spring effective on the hanger between the feed-rolls and at a point nearer to one of the feed-rolls than to the other to urge both feed-rolls toward the platen, a cast-off device 10 effective to apply roll-withdrawing force to the hanger between the feed-rolls at a point nearer to the feed-roll where the spring is effective than to the other feed-roll, but out of front-and-rear alignment 15 with the point on the hanger where the spring is effective, and means for guiding the hanger for up-and-down movement and for restraining the hanger against rocking movement.

20 21. In a typewriting machine, in combination, a platen, front and rear feed-rolls

normally occupying a position to co-operate with the lower part of the platen, a hanger common to both front and rear feed-rolls, a spring effective on the hanger between the feed-rolls and at a point nearer the rear 25 than to the front feed-roll to urge both feed-rolls toward the platen, a cast-off device effective to apply roll-withdrawing force to the hanger at a point between the front feed-roll and the point at which the spring is effective on the hanger, and at a point nearer to the rear feed-roll than to the front feed-roll, and means for guiding 30 the hanger for up-and-down movement and for restraining the hanger against rocking movement. 35
